UNITED STATES PATENT OFFICE.

HENRY P. CLAUSEN, OF MOUNT VERNON, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,345,348.

Specification of Letters Patent. Patented July 6, 1920.

Application filed June 25, 1917. Serial No. 176,808.

To all whom it may concern:

Be it known that I, HENRY P. CLAUSEN, a citizen of the United States, residing at Mount Vernon, in the county of Westchester and State of New York, have invented certain new and useful Improvements in Telephone-Exchange Systems, of which the following is a full, clear, concise, and exact description.

10 This invention relates to telephone exchange systems, and more particularly to such systems employing automatic ringing trunk circuits between originating ("A") or terminating ("B") boards for interconnecting telephone lines terminating at the different boards, which may be in the same or different central offices.

In such systems it is frequently desirable that the connection to the wanted line including the trunk circuit and a link circuit be built up and that the application of ringing current to the wanted line be delayed until such time as the operator at the "A" board determines. This is particularly desirable in working connections between local and toll lines, when it is economical to hold the local line while building up the connection between the link circuit and an expensive toll line. In systems of this character, 30 it is usual for the operator at the "A" board to have complete charge of the supervision over such connections, so the connection to the wanted local line may be built and held awaiting the building up of the connection 35 with the more expensive toll line, at which time the operator may cause the wanted local line to be signaled. It is the object of this invention to provide a system for accomplishing the desirable results above set forth.

40 In accordance with this invention, a trunk circuit extending between an "A" and a "B" board may be connected at its incoming end with a telephone line, and a link circuit may be connected with the outgoing end thereof without applying ringing current to the telephone line until such time as the operator at the "A" board determines. There is associated with the trunk circuit 45 apparatus, by means of which, when the operator at the central office X causes the momentary actuation of a switch, ringing current is connected with the wanted telephone line and is then automatically dis-

connected therefrom upon the response of 55 the called subscriber.

For a complete understanding of this invention, reference should be had to the following description considered in connection with the accompanying drawing showing a 60 telephone exchange system containing one embodiment of this invention. In the drawing, there is shown a telephone line A which may be connected in any desired manner with a cord circuit C, located at a central 65 office X, and another telephone line B terminating at a central office Y, at which is located the incoming end of a trunk circuit D, the outgoing end of which is located at the central office X. For convenience, the 70 operator at central office X will be herein-after designated as the "A" operator, and the operator at central office Y as the "B" operator.

Assuming that it is desired to build up a 75 connection with and hold line B while the connection with line A is being built up and to delay the application of ringing current to line B until the connection with line A has been built up, the "A" operator communicates with the "B" operator over an 80 order wire circuit (not shown) and receives a trunk assignment, after which the "A" operator inserts plug 5 of the cord circuit C into the jack 6 of the trunk circuit D and 85 the "B" operator inserts plug 15 of trunk circuit D into jack 16 of line B. The insertion of the plug 5 into the jack 6 causes the lighting of supervisory lamp 36 and the 90 operation of relay 7. Supervisory relay 8 does not operate when in series with the high resistance left-hand winding of relay 7, but does operate when the low resistance right-hand winding thereof is included in the 95 circuit in parallel with the left-hand winding, as will more fully hereinafter appear. If the "B" operator has not inserted the plug 15 into the jack 16 the operation of relay 7 causes the lighting of lamp 9 over a circuit from battery through the lamp 9 contact of 100 relay 7, lower normal contact of relay 10 and resistance 11 to ground, but if the plug 15 has been inserted into jack 16, the lamp 9 will not be lighted by the operation of relay 7. The insertion of the plug 15 of 105 trunk circuit D into the jack 16 of line B by the "B" operator causes the operation of relay 10 and cut-off relay 17. Relay 10, in

operating, closes its contacts 18 and 19 before contact 20 thereof is closed, so that fast operating relay 21 operates before the slow-to-operate relay 22 can attract its armatures. The operating circuit for relay 21 may be traced from battery through the normal contact of relay 22, winding of relay 21, contact 18 of relay 10, contact of relay 7, winding of relay 10, sleeve contacts of the plug 15 and the jack 16 and the winding of cut-off relay 17 to ground, relay 21, in operating, completes a locking circuit for itself, which includes its alternate contact. The winding of relay 21 is now connected in parallel with the lamp 9, forming a shunt about and effacing this lamp. Upon the closure of contact 20 of relay 10, following the closure of contact 18, slow-operating relay 22 is actuated over a circuit from battery through the winding of relay 22, contacts 20 and 18, contact of relay 7, winding of relay 10, sleeve contacts of the plug 15 and the jack 16 and the winding of cut-off relay 17 to ground. Relay 22, in operating, opens its normal contact in the initial energizing circuit of relay 21, and closes, at its right-hand alternate contact, a short circuit for and prevents the operation of the ringing relay 25. This short circuit also includes the alternate contact of relay 21. When the building up of the connection with line A is accomplished the "A" operator is suitably advised, and momentarily actuates a key 27, causing the momentary opening of the circuit of relay 7, which releases its armature and then attracts the armature again upon the closure of the circuit. The release of the armature of relay 7 opens the circuit of relay 21, which releases its armature, opening the short circuit of ringing relay 25. Relay 22 is made slow in releasing so that it does not release its armatures while the contact of relay 7 is open for the short time. Upon the closure of the contact of relay 7 following the restoration of key 27 to normal position, ringing relay 25 immediately operates over a circuit from battery through the winding of ringing relay 25, right-hand alternate contact of relay 22, normal contact of relay 21, contact of tripping relay 30, left-hand alternate-contact of relay 22, contact 18, contact of relay 7, winding of relay 10, sleeve contacts of the plug 15 and the jack 16 and the winding of cut-off relay 17 to ground. The operation of ringing relay 25 connects a source of ringing current 31, through the winding of tripping relay 30, to line B, thereby to cause the actuation of call bell 32 at the station of line B. In responding to the operation of the call bell, subscriber B removes the receiver from the switchhook, whereupon tripping relay 30 operates, opening its contact, thereby removing a short circuit from the winding of re-

lay 21. Relay 21 thereupon operates and locks up, establishing a short circuit for ringing relay 25, which then releases its armatures to disconnect ringing current from the line and to complete the talking circuit. 70 Immediately upon the completion of the talking circuit, supervisory relay 33 is operated, thereby completing a circuit, through the right-hand winding of relay 7, to connect it in parallel with the left-hand winding. 75 The resistance in circuit with supervisory relay 8 is thereby decreased, permitting this relay to operate and establish a shunt circuit including resistance 28 for calling supervisory lamp 36, whereby the lamp 80 is effaced.

At the conclusion of the conversation, the subscribers restore their respective receivers to the switchhooks. The restoration of the receiver to the switchhook by subscriber B 85 causes the deenergization of supervisory relay 33, which, in releasing its armature, opens the circuit of and removes the right-hand winding of relay 7 from the circuit which includes the winding of supervisory 90 relay 8, thereby causing the release of supervisory relay 8. Upon the release of this supervisory relay, calling supervisory lamp 36 is lighted to furnish the "A" operator a disconnect signal. The "A" operator may now withdraw the plug 5 from the jack 6, restoring the apparatus of the cord circuit C to normal, and causing the release of relay 7, which opens up the shunt circuit about the lamp 9 to permit the lighting thereof. 100 The lighting of this lamp 9 serves as a disconnect signal to the "B" operator, who may now withdraw the plug 15 from the jack 16, thereby restoring to normal all apparatus of the trunk circuit D and the telephone 105 line B.

If desired, the momentary release of the trunk relay 7 may be accomplished by the momentary withdrawal of the plug 5 from the jack 6. The key 27 may then be omitted. 110

What is claimed is:

1. A telephone exchange system comprising a trunk circuit extending from a first to a second switchboard, a link circuit at the first switchboard connected with the trunk circuit, a source of ringing current, a telephone line, apparatus responsive to the connection of the trunk circuit with the telephone line for preventing the connection of the source of ringing current to the telephone line, a switch at the first switchboard, means responsive to the actuation of the switch to connect the source of ringing current to the line, and a relay energized upon the closure of the telephone line to disconnect the ringing current therefrom. 120

2. A telephone exchange circuit comprising a trunk circuit extending from a first to a second switchboard, a link circuit at the first switchboard connected with the trunk 130

circuit, a source of ringing current, a telephone line, apparatus responsive to the connection of the trunk circuit with the telephone line for preventing the connection of 5 the source of ringing current to the telephone line, a switch at the first switchboard, switching mechanism responsive to the actuation of the switch to connect the source of ringing current to the telephone line, and 10 an electromagnetic switch responsive to the closure of the telephone line for causing the disconnection of the source of ringing current therefrom.

3. A telephone exchange system comprising 15 a trunk circuit extending from a first to a second switchboard, a link circuit adapted to be connected with the trunk circuit, a source of ringing current, a telephone line terminating at the second switchboard, a ringing relay associated with the 20 trunk circuit for connecting the source of ringing current to the line and maintaining such connection until the subscriber answers, an energizing circuit for the ringing relay, 25 means operated upon the connection of the link circuit with the trunk circuit for preventing the establishment of said energizing circuit, and a switch at the first switchboard adapted when actuated to cause the 30 release of said means thereby causing the energization of said ringing relay for connecting the source of ringing current with the line.

4. A telephone exchange system comprising 35 a trunk circuit extending from a first to a second switchboard, a link circuit at the first switchboard adapted to be connected with the trunk circuit, a telephone line terminating at the second switchboard, 40 a signaling device, a relay in the trunk circuit energized upon the connection of the link circuit with the trunk circuit to cause the operation of the signaling device, a source of ringing current, a ringing relay 45 associated with the trunk circuit for connecting the source of ringing current to the line and maintaining such connection until the subscriber answers, means responsive to the energization of the trunk relay, a 50 disabling circuit for the ringing relay established upon the operation of such means, and a switch at the first switchboard, said trunk relay being deenergized upon the momentary actuation of the switch to cause the 55 release of said means thereby opening the disabling circuit of the ringing relay and causing the operation thereof to connect the source of ringing current to the telephone line.

5. A telephone exchange system comprising 60 a trunk circuit extending from a first to a second switchboard, a link circuit at the first switchboard connected with the trunk circuit, a telephone line terminating at the 65 second switchboard, a source of ringing cur-

rent, a ringing relay for connecting the source of ringing current to the telephone line, a fast and a slow-operating relay energized upon the connection of the trunk circuit with the telephone line to prevent the 70 operation of the ringing relay, a locking circuit for the fast-operating relay completed upon the energization thereof, a switch at the first switchboard, and a switching device responsive to the actuation of the 75 switch for opening the locking circuit and thereafter coöperating with the fast-operating relay to cause the operation of the ringing relay.

6. A telephone exchange system comprising 80 a trunk circuit extending from a first to a second switchboard, a link circuit at the first switchboard, a trunk relay in the trunk circuit energized upon the connection of the link circuit therewith, a telephone line terminating at the second switchboard, a source of ringing current, a ringing relay adapted when energized to connect the source of ringing current to the telephone line, a fast and a slow-operating relay energized upon 85 the connection of the trunk circuit with the telephone line to prevent the energization of the ringing relay, a locking circuit for the fast-operating relay completed upon the energization thereof and including a 90 contact of the trunk relay, a switch at the first switchboard controlling the trunk relay, and an energizing circuit for the ringing relay completed upon the deenergization of the fast-operating relay followed by the 95 energization of the trunk relay.

7. A telephone exchange system comprising 100 a trunk circuit extending from a first to a second switchboard, a link circuit at the first switchboard, a trunk relay in the trunk circuit energized upon the connection of the link circuit therewith, a telephone line terminating at the second switchboard, a source of ringing current, a ringing relay adapted 105 when energized to connect the source of ringing current to the telephone line, a fast and a slow-operating relay energized upon the connection of the trunk circuit with the telephone line to prevent the energization of the ringing relay, a locking circuit for the 110 fast-operating relay completed upon the energization thereof and including a contact of the trunk relay, a switch at the first switchboard controlling the trunk relay, an energizing circuit for the ringing relay completed upon the deenergization of the fast-operating relay followed by the energization 115 of the trunk relay, and a tripping relay responsive to the closure of the telephone line and coöperating with the fast-operating relay to cause the deenergization of the ringing relay.

8. A telephone exchange system comprising 120 a trunk circuit extending from a first to a second switchboard, a link circuit at the 125

first switchboard connected with the trunk circuit, a telephone line terminating at the second switchboard, a source of ringing current, a ringing relay adapted when operated 5 to connect the source of ringing current to the telephone line, a local relay responsive to the connection of the trunk circuit with the telephone line, a disabling circuit for the ringing relay established upon the energization 10 of the local relay, a switch at the first switchboard, and a switching device responsive to the actuation of the switch for rendering the disabling circuit ineffective thereby permitting the energization of the ringing relay to connect 15 the source of ringing current to the line.

9. A telephone exchange system comprising a trunk circuit extending from a first to a second switchboard, a link circuit at the first switchboard connected with the trunk 20 circuit, a telephone line terminating at the second switchboard, a source of ringing current, a ringing relay adapted when energized to connect the source of ringing current with the telephone line, a fast and a 25 slow-operating relay energized upon the connection of the trunk circuit with the telephone line, a disabling circuit for the ringing relay established upon the energization of the fast and slow-operating relays and

including a contact of the fast-operating relay, a switch at the first switchboard, and a switching device responsive to the actuation of the switch for rendering the disabling circuit ineffective thereby permitting the energization of the ringing relay to connect 30 the source of ringing current to the line. 35

10. A telephone exchange system comprising a trunk circuit extending from a first to a second switchboard, a link circuit at the first switchboard adapted to be connected with the trunk circuit, a telephone line terminating at the second switchboard, a switch at the first switchboard, a source of ringing current, a ringing relay associated with 40 the trunk circuit for connecting the source of ringing current to the line, and means responsive to the connection of the link circuit with the trunk circuit to establish a disabling circuit for the ringing relay, said 45 means being momentarily released upon the actuation of the switch to open the disabling circuit of the ringing relay thereby causing the operation thereof to connect the source of ringing current to the line. 50 55

In witness whereof, I hereunto subscribe my name this 22nd day of June, A. D. 1917.

HENRY P. CLAUSEN.
